UNITED STATES PATENT OFFICE.

MAYO CLODFELTER, OF CHICAGO, ILLINOIS.

STROKE-CHANGING MECHANISM.

Application filed July 15, 1924. Serial No. 726,227.

To all whom it may concern:

Be it known that I, MAYO CLODFELTER, a citizen of the United States, residing at Chicago, in the county of Cook and State 5 of Illinois, have invented certain new and useful Improvements in Stroke-Changing Mechanism, of which the following is a specification.

This invention relates to mechanism for 10 varying the stroke of engines, particularly internal combustion engines.

An important object of the invention is to 15 provide means in connection with engines for varying the stroke thereof according to the number of revolutions per minute.

A further object of the invention is the provision of a mechanism of this character which will operate automatically and materially increase the efficiency of the engine. 20

A still further object of the invention is the provision of a mechanism of this character which is comparatively simple in construction, durable and efficient for this purpose. 25

Other objects and advantages of this invention will be apparent during the course of the following description.

In the accompanying drawings forming a 30 part of this specification and in which like numerals are employed to designate like parts throughout the same:

Figure 1 is a plan view showing my improved device mounted upon the crank shaft,

Figure 2 is a side elevation of the same, 35 Figure 3 is a side elevation taken on the line 3—3 of Figure 2,

Figure 4 is a vertical sectional view taken on the line 4—4 of Figure 2,

Figure 5 is a transverse sectional view taken on the line 5—5 of Figure 2, and 40

Figure 6 is an enlarged sectional view showing the construction of the stop mechanism.

As it is well understood by those familiar 45 with devices of this character, internal combustion engines when traveling at a high rate of speed lose much of their efficiency due to the small amount of explosive gas fed into the cylinders and a corresponding loss in compression. It is to offset this loss in efficiency that my improved mechanism is employed, this mechanism being adapted to automatically lengthen the stroke of the

engine and compensate for the loss of power 55 occasioned by the increased speed thereof.

In the drawings, wherein for the purpose of illustration is shown the preferred embodiment of my invention, the numeral 10 generally indicates a conventional type of 60 crank shaft comprising a comparatively long crank arm 11, a shorter crank arm 11' and crank pins 12. I have also shown a conventional type of connecting rod 13 mounted upon the pin positioned between 65 the long and short arms.

Referring more particularly to my improved device, I provide an eccentric 14 preferably formed of two sections having a suitable opening formed therein for engagement with the crank pin, these eccentric sections being securely retained upon the crank shaft by means of the connecting rod bearing cap. On one extremity of the eccentric is mounted a toothed gear 15 this gear being rigidly secured to the extremity 70 of the eccentric and adapted to rotate the same about the crank pin. 75

A T-shaped groove 16 is formed on the outer face of the crank arm 11, this groove 80 extending very nearly the entire length of the crank arm in the center thereof.

A sliding block member 17 having a T-shaped bar formed on one face thereof and adapted to engage the groove 16 formed in the crank arm is adapted to reciprocate on the outer face of the arm. Formed on the narrow side of the block 17 near the lower extremity thereof is a toothed rack 19, this rack being provided with teeth suitable to engage the teeth formed on the gear 15, the rack being so positioned as to engage the teeth in order to impart rotary movement to the gear. The outer face of the block 17 is also provided with a T-shaped groove 20, 90 a rectangular stop lug 21 being positioned in the lower portion of this groove to limit movement of a member to be mounted therein. 95

A rectangular weight member 22 is slidably mounted on the outer surface of the block 17, this weight member having a T-shaped bar formed on the inner face thereof for engagement with the slot 20 formed on the outer face of the block 17. It is 100 obvious that the weight 22 is slidably mounted upon the block 17 and this block is likewise slidably mounted upon the crank 105

arm, the downward movement of the weight 22 being limited by the lug 21 while movement of the block 17 is limited by the lower lug 22' and the upper extremity of the 5 groove 16.

As it is necessary to provide means for locking the weight in position after movement thereof, I provide a pair of sliding 10 dowel pins 24 slidably mounted in the sliding block 17. These pins are mounted in circular grooves 24' formed in the block 17, the pins comprising a cylindrical shank 25 having an enlarged circular shoulder 26 formed on the lower extremity while the 15 upper extremity carries a semi-circular knob 27 threadedly mounted upon the upper extremity of the shank 25 and adapted to normally extend above the block. A guide collar 28 is formed in the groove 24', the central portion thereof being provided with a circular opening adapted to receive the shank 25 and permit the same to slide therein. A coiled spring 29 is positioned about the shank 25 between the collar 28 and the 20 upper knob 27, this spring having a tendency to force the pin in the raised position as clearly shown in Figure 6. A suitable circular recess 30 is formed in the outer face of the crank, this recess being adapted to 25 receive the shoulder 26 on the pin when the same is in the locked position. In order to automatically throw the pin in engagement with the crank arm the sliding weight 22 is provided with arcuate grooves 31 formed 30 near the upper and lower extremities thereof and adapted to engage the knob 27 formed on the upper portion of the pin members. It is obvious that movement of the weight 35 will cause the arcuate groove 31 to slide over the knob 27 on the pin and force the same downwardly into the recesses formed in the crank arm thereby retaining the sliding block 17 rigidly in position.

In order to retain the sliding weight and 40 block members in their upper position, that is, to reduce the stroke while the engine is operating at a comparatively low speed, I provide a pair of coiled compression springs 32 and 33, these springs being mounted in 45 the T-shaped grooves formed in the outer face of the sliding block 17 and the crank arm respectively, these springs bearing 50 against the lower portions of the weight and block and forcing the same to the upper 55 position.

In operation, as the speed of the engine increases beyond a certain R. P. M. at 60 which the springs are set, the sliding weight 22 will be thrown by centrifugal force towards the outer extremity of the crank arm, this movement releasing the upper pin 24 and causing similar movement of the block member 17. When the lower dowel pin aligns with the lower recess 30 formed 65 in the crank arm the weight member 22 will

force the pin into this recess and lock the same therein causing the sliding block member and weight to retain these positions until the speed of the motor is reduced. It is further to be noted that this movement 70 of the sliding block 17 will cause similar movement of the rack 19 formed thereon, thus rotating the toothed gear 15 carrying the eccentric. As the eccentric is rotated about the crank pin a corresponding increase in stroke length will result thus accomplishing the purpose intended. As the speed of the engine is lowered the compression springs 32 and 33 will return the weight member 22 and sliding block 17 to 75 their normal position with a corresponding reduction in stroke length.

It is to be understood that the form of my invention herewith shown and described is to be taken as the preferred example of 80 the same, and that various changes as to the shape, size and arrangement of parts may be resorted to without departing from the spirit of the invention, or the scope of 85 the subjoined claims.

Having thus described my invention, I 90 claim:

1. A device of the character described comprising a sliding block member having a T-shaped bar formed thereon, a sliding weight member slidably mounted within a suitable groove formed in the sliding block member, a toothed rack member formed on the side of the said sliding block, means for normally retaining the said sliding block and weight member in a raised position, and means for locking the said sliding block.

2. A device of the character described comprising a sliding block member having a groove formed on one side thereof, a T-shaped bar formed on the opposite side of the said block member, a toothed rack formed on one extremity of the said block member, a sliding weight member having a T-shaped bar formed on one side adapted to slidably move within the groove formed within the said block member, spring members adapted to normally retain the said block and weight members in a set position, and sliding pin members adapted to retain the said block in locked position.

3. In combination with an internal combustion engine crank shaft, of an eccentric mounted on the pin of the said crank shaft, a gear mounted on one extremity of the said eccentric, a sliding block member mounted on one side of the crank shaft arm, a toothed rack adapted to rotate the eccentric mounted on one side of the sliding block member, a weight member slidably mounted on the outer face of the said block, and means for normally retaining the said sliding block in a certain position.

4. In combination with an internal com-

bustion engine, and a crank shaft mounted on the said engine, of an eccentric rotatably mounted on the pin of the said crank shaft, a toothed gear mounted on one end of the 5 said eccentric, a sliding block member having a projecting bar formed on one side adapted to move in a suitable groove formed in the crank shaft arm, a toothed rack member formed on one extremity of the said block, a slidable weight having a projection formed on one side thereof adapted to slide within a suitable groove formed in the said block member, coiled spring members mounted in the grooves and adapted to retain the 10 said slidable members in an inoperative position, and a plurality of slidable pin members mounted in the slidable block for locking the same in position.

5. In combination with an internal combustion engine, and a crank shaft rotatably mounted in the said engine, of an eccentric formed of two sections mounted on the pin of the said crank shaft, a toothed gear formed on one extremity of the said ec-

centric, a slidable block member having a 25 T-shaped bar formed on one side thereof and adapted to slide in a suitable groove formed in the crank shaft arm, a toothed rack formed on the side of the said sliding block member and adapted to mesh with the 30 said toothed gear member, a sliding weight member having a T-shaped bar formed on one face thereof and adapted to slide in a suitable groove formed in the face of the block member, a pair of coiled compression 35 springs secured in the said grooves adapted to normally retain the sliding block and weight members near the inner extremity of the said crank shaft arm, and a plurality of dowel pins slidably mounted within suitable bores formed in the side of the block member for locking the same in position.

In testimony whereof, I have affixed my signature in the presence of two witnesses.

MAYO CLODFELTER.
